UNITED STATES PATENT OFFICE

MARIANO A. BOIX, OF MAYAGUEZ, PORTO RICO

COLLAR

Application filed March 30, 1926. Serial No. 98,557.

The present invention relates to improvements in wearing apparel, and more specifically to an improved collar of the turn down type.

5 The primary object of the invention is to provide a novel type of soft or semi-soft collars embodying a fold flap which may be readily swung to each side of the neck band of the collar for permitting of either side of the 10 fold flap being disposed outermost and exposed to view should one side of the fold flap become soiled.

A further object of the invention is to provide an improved reversible collar embodying features of construction whereby when the various sections forming the collar are secured together, no undesirable bulges will be formed which may be unsightly or cause discomfort to the wearer of the collar.

20 A still further object of the invention is to provide an improved reversible collar which is neat in appearance, which may be economically manufactured, and which will present a like appearance when worn in either of its 25 reverse positions.

Other objects and advantages of the invention will be apparent during the course of the following detail description, taken in connection with the accompanying drawing forming 30 a part of this specification and in which drawing:

Figure 1 is a perspective view of a collar constructed in accordance with my invention.

Figure 2 is a perspective view of the collar 35 and showing certain portions in dis-assembled relation for illustrating the novel construction of the collar.

Figure 3 is a view illustrating the fold flap of the collar in blank form, and the neck band 40 of the collar in a position for receiving the fold flap.

Figure 4 is a fragmentary view of one end 45 of the improved collar and showing portions broken away to illustrate details of construction.

Figure 5 is an enlarged transverse section on line 5—5 of Figure 4.

Referring to the drawing in detail, and wherein similar reference characters designate corresponding parts throughout the sev-

eral views, the letter A designates the improved collar, embodying a neck band B and a reversible fold flap C.

The neck band B which may be made of any suitably soft material, embodies a pair of symmetrically formed portions 10 and 11. Each of the neck band portions 10 and 11 is provided at its marginal edges with inwardly turned folds 12. As clearly illustrated in Figure 2, the folds extending along the top 55 marginal edges of the neck band portions are of considerable width and are reduced in width at the tab portions 13 of the band as at 14. By so reducing the folds 14 at the tab portions of the band, a neater appearance will 60 be formed by the tabs when connected in overlying relation to the neck band of a shirt. In securing the band sections 10 and 11 together, the same are first stitched along their lower edges and the tab portions 13 by a line 65 of stitching 16 and then turned inside out for forming the folds 12 and 14. When in this position, and as illustrated in Figure 3, the upwardly projecting edges 17 may be turned inwardly of the band portions for providing 70 the folds 12 at the top marginal edge of the band. By so having the folds 12 of considerable width along the top marginal edges of the band portions, it will be seen that when 75 the folds are turned inwardly of the band portions as in Figure 5, a stiffening band will be formed along the upper edge of the neck band having sufficient depth to insure proper folding of the flap C to either side of the neck band along the upper edge of the stiffening 80 band without likelihood of the folds tending 85 to roll outwardly. The rows of stitching 18 may then be run around the lower edge of the band and the tab portions as illustrated in Figure 3, but it is desirable that this 90 stitching be omitted until associating of the fold flap with the neck band, and in which case the stitchings 18 for forming the seams at the marginal edges of the neck band will also serve for securing the fold flap to the neck 95 band when continued along the upper marginal portion of the band.

Suitable button holes 19 may be provided adjacent each end of the neck band for securing the ends of the collar to the front of the 100

shirt band, and a button hole 20 may be provided midway of the band for attachment to the rear portion of the shirt band as is the usual method of attaching a collar to a shirt band.

5 The fold flap C, and which may also be formed of any suitably soft material, is of a length substantially equal to the length of the neck band B, exclusive of the tab portions 13, and of a width slightly greater than twice the height of the neck band. The fold flap when cut in blank form, has each corner thereof removed as at 21, and has substantially V shaped notches 22 provided at each end of the flap in a line forming the longitudinal center of the flap. The flap C is intended to be folded on its longitudinal center line 23, and the wings 24 at each end of the flap are turned inwardly between the folded portions of the flap as illustrated in Figures 2 and 4. It will be seen by observing Figure 4, that the notches 22 will prevent any bulging of the material at the ends of the fold line 23. After the flap C has been folded upon itself and a seam has been provided along its lower and end edges by means of stitchings 25, the fold portions 26 of the flap may be inserted in the pocket formed along the top edge of the neck band and secured thereto by a continuation of the stitchings 18. These fold portions 26 are preferably of a width equal to the width of the folds 12. By observing Figure 5, it will be seen that by so removing the portions 21 from the corners of the fold flap, that merely two thicknesses of folds will extend between the folds 12 of the neck band C at the ends of the fold flap. Were these portions 21 not removed as shown, the wings 24 which form the folds 30 at the ends of the fold flap, 20 would also extend between the folds 12 and thus cause an undesirable thickness of material.

It will readily be apparent that the fold flap C may be swung to each side of the neck band B and will present an identical appearance when in either of its adjusted positions with respect to the neck band.

45 From the foregoing description it will be apparent that a novel type of reversible collar has been provided, embodying features of construction whereby no undesirable thickened portions are formed by securing of the various sections together, and one wherein the fold flap is reversible upon the neck band 50 of the collar and in a manner for presenting a clean appearance to the collar should one side of the fold flap become soiled.

Changes in detail may be made to the specific form of the invention herein shown 60 and described, without departing from the spirit of the invention or the scope of the following claim.

I claim:

65 A reversible collar comprising a neck band embodying a pair of symmetrically formed

sections connected to provide a pocket extending along the top edge of the neck band, and a fold flap embodying connected superposed layers having wings turned inwardly between the layers along each end edge of each layer, said wings having their like ends cut away and forming folds having ends spaced inwardly from one longitudinal edge of the fold flap, the fold flap having said longitudinal edge for the depth of the cut away ends of the wings secured in the pocket of the neck band.
